UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA

FEEDER FOR INGOT MOLDS.

Application filed December 29, 1923. Serial No. 683,502.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Feeders for Ingot Molds, of which the following is a specification.

Our invention relates to improvements in feeders for ingot molds.

The object of our invention is to provide a sectional feeder for ingot molds which when placed in the mold the sections will be retained in their normal operative positions so that the usual pouring operation can take place and at the same time provide a feeder which will prevent "piping" and also reduce "segregation" to a minimum.

Another object of our invention is to provide a feeder of this character which is provided with means for supporting it in the upper end of the mold and said means also serving as means for strengthening the feeder.

Another object of our invention is to provide a feeder having supporting means contained in each section so that each section is independently supported on the top of the mold.

A further object of our invention is to provide a sectional feeder which can be assembled out of the mold and held together by a band so that the mold can be shipped in sections and readily assembled.

Another object of our invention is to provide a feeder of uniform sections so that the edges thereof will fit each to each without difficulty in assembling and at the same time prevent movement after assembling.

A still further object of our invention is to provide a feeder of this character which is provided with the supporting and strengthening means so arranged that a flat band fitted to the contour of the outer periphery can be placed around the feeder and not interfere with the entrance of the feeder into the neck of the mold.

A still further object of our invention is to provide a simple, cheap and effective feeder having certain details of structure and combination of parts hereinafter more fully set forth.

In the accompanying drawings:

Figure 1 is a perspective view of an ingot mold showing our improved feeder supported within the upper end thereof.

Figure 2 is a vertical sectional view of an ingot mold showing the feeder partly in section.

Figure 3 is a vertical sectional view of an ingot mold showing the feeder partly in section and showing a band holding the several sections together.

Figure 4 is a top plan view of Figure 3.

Figure 5 is a top plan view of a modified form of feeder.

Figure 6 is a still further modified form of feeder.

Figure 7 is a vertical sectional view of Figure 5 showing the feeder partly in elevation.

Figure 8 is a vertical sectional view of Figure 6.

Figure 9 is a perspective view of an ingot mold showing the modified form of feeder therein.

Figure 10 is a perspective view of an ingot mold showing a still further modified form of our improved feeder.

Referring now to the drawings 1 represents the ingot mold and 2 the feeder. As shown in the drawings the feeder 2 is of a circular form and formed of four sections 3, 4, 5 and 6 the connection or joint between the same being in a radial line of the circle so that when the four sections are placed in the neck of the mold they are locked together against inward movement as shown in Figure 1 of the drawings. The outer periphery shown in each section is provided with ribs 7 and 8 the lower ends of which rest on the upper end of the mold and whereby each section is independently supported by the mold. While we have shown two ribs carried by each section it will be understood that any other number could be used.

In Figures 3 and 4 we have shown a band 9 extending around the outer periphery of the several sections and of a shape snugly fitting the walls of the sections and the ends of the band held together by the clamping member 10 all of which is shown and described in our Patent No. 1,431,853. The feeder being divided in sections the abutting walls of which being arranged in a radial line, it will be seen that when the sections

have their walls abutting either against the mold or when the band is employed to hold them together before the feeder is placed in the mold, the sections cannot move or 5 collapse inwardly and are firmly locked together.

In Figure 5, the feeder 11 is made of four sections 12, 13, 14, and 15 the walls of which are slightly curved and are also provided 10 with ribs 16 supporting the feeder in the upper end of the mold. The abutting walls of the several sections are like that shown in Figures 1 to 4 inclusive arranged in a radial line so that the independent sections 15 cannot be moved inwardly. A band 9 constructed like that in Figures 3 and 4 are employed to hold the sections together when it is desired to form a complete feeder so that it can be assembled and placed in the mold 20 as a unit.

In Figures 6 and 8 we have shown a rectangular feeder the abutting walls 17 of which are also so cut that the sections cannot be collapsed inwardly when used in the 25 mold or when set up outside of the mold and held together by a band.

In Figure 9 we have shown a fluted feeder 18 made up of four sections 19, 20, 21, and 22 and the outer walls of which sections being provided with vertically disposed rib 23 which is adapted to rest upon the upper edge of the mold and supporting it within the mold. These ribs on each side at the point of contact with the body of the feeder 30 are provided with scores 24 and 25 which weakens the ribs and allows the same to be broken off when desired. The ribs intermediate their upper and lower ends are cut away so that the band 9, to conform with the 40 outer periphery, may pass therein and whereby the band does not have to be shaped to correspond with the outer contour of the ribs.

In Figure 10 we have shown a shoulder 45 feeder 26 made up of four sections 27, 28, 29 and 30 cut at an angle at the corners so that when the same is placed in the mold the independent sections cannot move inwardly, or when the band is employed 50 around the outer periphery of the shoulder, the sections cannot collapse.

Having thus fully described our invention what we claim is:—

1. A feeder for ingot molds comprising 55 a series of sections, the abutting walls thereof being so arranged as to prevent movement.

2. A feeder for ingot molds comprising 60 a series of longitudinal sections, each section having outwardly extending independent supporting means.

3. A feeder for ingot molds comprising 65 a series of sections, each section having a projection, adjacent its upper end adapted to support the section independently,

4. A feeder for ingot molds comprising a series of independent sections, each section having one or more ribs on its outer periphery adjacent its upper end and adapted 70 to support the section in the mold.

5. A feeder for ingot molds comprising a series of independent sections, each section having a series of projections adjacent its upper end adapted to support the section 75 when in the upper end of the mold.

6. A feeder for ingot molds comprising a series of sections the abutting walls of which are so arranged that when the sections are placed in the mold they are locked against inward movement and projections 80 carried by the outer periphery of each section and adapted to support the sections independently in the mold.

7. A feeder for ingot molds comprising a series of sections the abutting walls of 85 which are so arranged the sections cannot move inwardly and a series of projections carried by the outer periphery of the sections adjacent their upper ends whereby the sections are independently supported within 90 the upper end of the mold.

8. A feeder for ingot molds comprising a series of independent sections, each section having a series of longitudinal ribs on its outer periphery adjacent its upper end and 95 whereby each section is independently supported at the upper end of the mold.

9. A feeder for ingot molds comprising a series of independent sections, longitudinal extending supporting means carried by 10 the outer periphery of each section adjacent its upper end and adapted to support the same in the upper end of the mold and a band extending around the outer periphery 10 of the several sections and holding the same in their assembled relation.

10. A feeder for ingot molds comprising a series of sections, each section having longitudinal extending ribs on their outer periphery and having cut away portions intermediate their ends and a band securing the sections together and passing through the 11 cut away portion of the ribs.

11. A feeder for ingot molds comprising a series of sections longitudinal ribs carried by the outer periphery and having opposite scores adjacent the body of the sections, said ribs having cut away portions intermediate their upper and lower ends and a band passing around the several sections 11 and passing through the cut away portions of the ribs.

12. A feeder for ingot molds comprising a series of longitudinal sections having thickened portions forming supporting means.

In testimony whereof we affix our signatures.

BLOOMFIELD H. HOWARD.
ERNEST J. TURNER.
